DESIGN FOR A COMBINATION DESK UNIT

Daniel Shatt, New York, N. Y.

Application June 29, 1939, Serial No. 85,755

Term of patent 7 years

To all whom it may concern:

Be it known that I, Daniel Shatt, a citizen of the United States, residing at New York, in the county of New York, State of New York, have invented a new, original, and ornamental Design for a Combination Desk Unit, of which the following is a specification, reference being had to the accompanying drawing, forming part thereof, in which:

Figure 1 is a perspective view of a combination desk unit showing my new design; and

Figure 2 is a perspective view from the opposite side of that shown in Figure 1.

The characteristic feature of my design resides in the grotesque representation of an animal figure having an open mouth containing a moistening pad simulating a tongue.

I claim:

The ornamental design for a combination desk unit, substantially as shown and described.

DANIEL SHATT.
